UNITED STATES PATENT OFFICE.

FREDERICK J. RAVLIN AND JOHN LOFGREN, OF CHICAGO, ILLINOIS.

RECEPTACLE-TO-CONDUIT-ATTACHING FITTING.

1,282,289.

Specification of Letters Patent. Patented Oct. 22, 1918.

Application filed December 3, 1914. Serial No. 875,277.

To all whom it may concern:

Be it known that we, FREDERICK J. RAVLIN and JOHN LOFGREN, citizens of the United States, both residing at Chicago, in the county of Cook and State of Illinois, have invented certain new and useful Improvements in Receptacle-to-Conduit-Attaching Fittings, of which the following is a specification.

10 Our invention relates to improvements in receptacles-to-conduit attaching fitting, that is to say coupling devices by which a hollow receptacle or the like may be attached, for support, to an electrical conduit. One of 15 the objects of our invention is to provide a construction whereby the installation of electrical appliances, to be served by the conduit-carried wire, may be facilitated by construction enabling the receptacle and 20 portions of the coupling to be loosely positioned on the conduit, out of the way of its extremity, while the base portion of the coupling, (with respect to which the electrical appliances will be positioned), is 25 properly attached to the conduit end and is easily accessible.

A further object of our invention is to provide a construction that will be weather proof, making a non-leaking joint between 30 the receptacle and conduit, through the attaching device.

Still another object of our invention is to provide a construction that insures adaptability of the coupling structure to surface 35 inequalities of the receptacle, and provide such coupling surfaces for co-operation with receptacle as will prevent injury to the latter, so that the coupling may advantageously be used in connection with enameled- 40 ware receptacles and the like, the surfaces of which are liable to damage.

In the drawings, wherein is illustrated an embodiment of our invention, in the single form of a coupling especially adapted for 45 attachment of an enameled lamp shade, having a deep lamp-socket-receiving receptacle, to the lamp wire carrying conduit.—

Figure 1 is a vertical sectional view with parts in elevation;

50 Fig. 2 is a vertical section with parts in elevation, showing the parts disassembled;

Fig. 3 is a transverse section on line 3—3 of Fig. 1; and

55 Fig. 4 is a detail suggesting the character of the enameled receptacle.

In the drawings 10 indicates in general a

lamp shade of a well known construction, often made of enameled steel, and having an extended receptacle-portion or throat 11, terminating in a top wall 12 that has a central 60 aperture 13 for attachment of the receptacle structure to a suitable conduit 14. While we do not intend to limit our invention to use with this particular form of receptacle or attached device, except so far as the same 65 may be specifically noted in the claim, our invention may be very advantageously employed in effecting connection between such a device and its conduit.

The conduit 14 is externally screw threaded as at 15 and for threaded connection therewith is provided a base 16, preferably of disk form, having a tubular extension 17 that is exteriorly threaded as at 18, the interior of the tubular structure having a 70 thread 15' that extends axially clear through the base. Where, as in the construction shown, auxiliary electrical devices, such as a lamp socket base 20, are to be secured to the base 16, threaded apertures 21 to receive the 75 attaching screws 22, may be provided in the base 16, or other adequate provision for attachment of the parts supported below may be made.

The upper surface of the base 16 provides an annular platform on which the top 80 wall of the receptacle 12 may find support, with its aperture 13 loosely surrounding the stem 17.

A nut 25 screwed down upon the external 90 threads 18 of the stem 17 affords a bearing, opposing the platform annulus of the disk 16, for retention of the receptacle in place, and the nut may, of course, be screwed down to exert any desired tension.

We prefer that yielding means, adapted when under pressure closely to conform to the clamped surface of the receptacle top 12, be interposed between said receptacle top and the clamping means, and in the particular construction shown such packing structures are provided both below and above the top portion 12 of the receptacle. Specifically 26 indicates an annular washer interposed between the bearing annulus of 100 the disk 16 and the under side of the receptacle wall 12, said packing washer being formed of relatively soft material, preferably elastic and water resisting. Specifically such washer may be made of prepared cork 105 so that under compression it will readily conform to any inequalities in the wall 12

of the receptacle and will yieldingly take up applied pressure so that if the receptacle is enameled the enamel may not be cracked or marred under pressure.

5 Likewise, above the receptacle wall 12 there is preferably provided a washer 27, capable of adapting itself to the surface of the receptacle and preferably made of lead, and guarded by a superimposed hard metal 10 washer 28, of steel or the like, to preserve it against the grinding action of the nut 25.

In setting a fixture, such as the receptacle 11 and its contained lamp base 20, the nut 25, washers 28 and 27 and receptacle 11 are 15 slipped upon the conduit 14, as suggested in Fig. 2, sufficiently far to be out of the way. The base structure 16, carrying the cork washer 26, is then screwed into place and supplies, in exposed position, the connecting 20 structure with respect to which the parts to be wired are located. The lamp socket section 20 may accordingly be easily placed in position and wired with the greatest facility, after which the receptacle 11 is lowered into 25 place, surrounding stem 17, the upper washers 27 and 28 are positioned thereon and the nut 25 is screwed home. Owing to the yielding packing employed, slight deviations from true surface in the top wall 12 30 of the receptacle are compensated for and no undue pressure is applied at high points on the surface 12 that, otherwise, would tend to crack the enamel. The upper and lower yielding washers, adapting themselves to the

receptacle, make a watertight joint between 35 the respective parts so that deterioration from rust is minimized and leakage of moisture into the receptacle is prevented.

Having thus described our invention, what we claim is:—

The combination with an exteriorly threaded conduit, a receptacle having an aperture of a diameter greater than that of the conduit, and a lamp socket; of a fitting 40 comprising a body part having a stem internally threaded for engagement with the threaded end of the conduit, and externally threaded for engagement by a clamping nut, a base portion on the lower end of the stem 45 extending radially therebeyond and affording bearing on its upper surface to support the receptacle, a clamping nut engaging the external threads of the stem above the receptacle and affording opposing bearing to clamp the receptacle against the base portion of the fitting and screw fastening means taking through the lamp socket insulating base from the lower end thereof into the upper side of the fitting base and within the 50 socket casing.

In testimony whereof we hereunto set our hands.

FREDERICK J. RAVLIN.
JOHN LOFGREN.

In the presence of—
GEO. T. MAY, Jr.,
MARY F. ALLEN.
